UNITED STATES PATENT OFFICE.

JAMES KELLY, OF EAGLE PASS, TEXAS, ASSIGNOR OF ONE-HALF TO GEORGE HONETSCHLAGER, OF STANFORD, MONTANA.

IGNITION SYSTEM FOR GAS-ENGINES.

1,353,045.

Specification of Letters Patent. Patented Sept. 14, 1920.

Application filed February 9, 1918. Serial No. 216,249.

To all whom it may concern:

Be it known that I, JAMES KELLY, a citizen of the United States of America, residing at Eagle Pass, in the county of Maverick and State of Texas, have invented new and useful Improvements in Ignition Systems for Gas-Engines, of which the following is a specification.

The present invention has reference generally to improvements in that class of inventions known as internal combustion engines and more particularly relates to an ignition system for gas engines.

As the principal aim and object of this invention contemplates the provision of a system of the above character designed to serve as a combination coil, distributor, interrupter and condenser for use in connection with storage batteries and low tensioned magnetos not timed to the engine shaft.

It is an additional object of this invention to provide a system of the above nature and character which is constructed in a compact unit and which is both dust and water-proof.

Among the other aims and objects of this invention may be recited the provision of a device of the character mentioned with a view to compactness, and in which the number of parts are few, the construction simple, the cost of production low and the efficiency high.

Other improvements and novel details in the construction and arrangement of the various parts of the apparatus will be brought out more in detail in the description to follow, which for a clear understanding of the invention, should be considered in connection with the accompanying drawings forming a part hereof, and wherein is disclosed for the purpose of illustration, a convenient and satisfactory embodiment of the invention. It is to be noted in this connection that minor changes in the construction and arrangement of parts may be made without departing from the spirit of the invention or the principle of operation of the various parts.

The invention is clearly illustrated in the accompanying drawings, in which:

Figure 1 is a vertical section of the invention;

Fig. 2 is a top plan thereof;

Fig. 3 is a transverse section taken on line 3—3 of Fig. 1;

Fig. 4 is a transverse section taken on line 4—4 of Fig. 1;

Fig. 5 is a plan view of the device with the main cover removed; and

Fig. 6 is a diagrammatic view.

Similar reference characters are employed in all the above described views, to indicate corresponding parts.

Referring now, more particularly, to the accompanying drawings there is provided a main or outer casing 1 formed desirably of metal and of a cylindrical configuration including side walls 2 and a bottom 3 having an opening 4 therein. A boss 5 is formed on the outer surface of the bottom about the opening while a collar 6 depends from the under surface of the bottom and about the opening for a purpose that will presently appear. An arm 7 extends from the body and is provided with an opening 8 in which is adapted to be mounted suitable means (not shown) for oscillating the casing. An inner cylindrical casing 9 is now employed and is disposed within the outer casing being provided in its bottom with a recess 10 in which is rigidly mounted a head 11 formed on the upper end of a shaft 12 which is adapted to be suitably geared to an internal combustion engine. This shaft is journaled in the collar 6 while the head 11 is in turn seated on the upper surface of the boss 5, this arrangement serving to effectively rotatably mount the inner casing within the outer casing which oscillates about the shaft.

Removably arranged in the non-conducting casing 9 is a core 13 about which is wound the primary coil 14 grounded to the head 11 at its lower end while wound about the primary coil is a secondary coil 15 which is also grounded at its lower or inner end 95 to the head 11 of the shaft.

Removably fitted on the upper edge of the inner casing 9 is a cover 16 therefor. An annular rib 17 is formed on the upper surface of the cover 16 adjacent the outer edge thereof and provides a recess 18 between the walls thereof. Both the cover and the rib are formed of non-conducting material while the upper surface of the cover adjacent the center thereof is provided with an annular recess 19 in which is fitted a metallic ring 20 having formed on its upper surface at suitably spaced points, cams 21 for a purpose that will presently appear. In this connection it is to be observed that the upper termi-

nal of the primary coil extends through the cover and is electrically connected to the ring 20. The rib and the cover are also provided with a recess 22 in which is slidably mounted a brush contacting head 23. Suitable resilient means such as a coil spring 24 is disposed in the recess and is tensioned so as to normally hold the head 23 flush with the upper edge of the rib while the spring in turn is connected to the upper end of the secondary coil so as to conduct current from this coil to the head.

Removably fitted on the upper edge of the main casing is a cover 25. This cover consists of a body 26 from the outer edge of which depends a flange 27 for removable engagement with the upper edge of the casing 1 while the body is further provided centrally thereof with a recess 28 for a purpose that will presently appear. The under surface of the body is still further provided with an annular recess 29 adjacent the outer edge thereof and accommodates the annular rib 17 when the cover 25 is in a closed position. The bottom of this recess is provided with another recess 30 in which is removably mounted an annular band 31 formed of non-conducting material. A plurality of distributor contact brushes 32 are mounted in the band 31 and are arranged in radial alignment with the cams 21 as indicated in Fig. 5 being designed to be contacted by a yieldingly mounted contacting brush head 23 during the rotation of the inner casing which carries the cover 17 so that current will successively pass from the contact brush head 23 to the contact brushes 32 formed integral with and projecting from the upper surface of the main cover 25. At points directly above the brushes 32 are binding posts 33 while conducting wires 34 are mounted within these posts and electrically connected to the said brushes 32 for a purpose that will presently appear.

Coöperating with the cams 21 which serve as contact breakers is the rocker arm 35 pivotally mounted between depending ears 36 in the under surface of the cover 25. A roller contact 37 is journaled on one end of the arm for engagement with the ring 20 and the cams 21. An eye 37' is formed on the opposite end of the arm and carries a contact point 37" which is normally disposed in contact with an adjusting screw 38, adjustably engaged in a sleeve 39 mounted in turn in an opening 40 in the cover. A conducting wire 41 is led from the sleeve and extends through the central binding post 42 formed on the upper surface of the cover 25. Suitable resilient means such as a leaf spring 43 has one end secured to the cover and its opposite end bearing against the arm so as to normally hold the contact point 37" against the lower edge of the screw 38. However, during rotation of the inner casing and os-

cillation of the outer casing the cams will cause the roller to move upwardly and the contact point 37" to move downwardly so as to break the circuit.

To prevent burning of the contact point 37" and the screw 38 another conducting wire 44 is led from the ears 36 and is connected to a condenser positioned in a recess 28. The sheets 45 of this condenser are arranged in spaced insulated relation with the sheets 46 of the other side of the condenser which is electrically connected to the conducting wire 41 which passes through the binding post 42.

In constructing the remainder of the system special reference will be had to Fig. 6 wherein it will be observed that conducting wires 47 are electrically connected respectively to the conducting wires 34 at their inner ends and have their opposite ends connected to spark plugs 48 so that current will be alternately conducted from the secondary coil to the spark plugs. Another conducting wire 49 is now employed and is led from the wire 42 and is adapted to be grounded as at 90 for instance to the engine casing. A series of batteries 50 are interposed in the conducting wire 49 while the passage of current through the conducting wire may be controlled by a switch 51.

The mode of operation of the present invention may be reviewed as follows: Current from the primary coil which is grounded to the ring 20 passes from the ring during the rotation of the casing 9 and oscillation of the casing 1 to the rocker arm 35 through the instrumentality of the roller contact 37 normally held on the ring and in the path of movement of the cams 21, while the contact 37" is normally positioned against the screw 38 so that current will flow from the arm through the screw 38 and thence through the wire 41 to the wire 49 and through the batteries where it is grounded to the engine casing (not shown). It follows 110 this course assuming that the switch is closed. The circuit is broken, of course, when the cams 21 are engaged by the roller contact which latter is raised to consequently move the contact 37" downwardly and out 115 of contact with the screw 38. Should the current be too strong some of it passes from the conducting wire 44 into the condenser composing the sheets 45 and 46 where it is quenched so as to avoid burning of the contact point 37" and the screw 38. The current from the secondary coil flows through the spring 22 and the contact brush head 23 and inasmuch as this brush head is yieldingly held in engagement with the band 31, 125 as the distributing contact brushes 32 move into engagement with the brush head 23 the current will pass to the conducting wires 34 and the conducting wires 47 so as to conduct the current to the spark plugs 48 allowing 130

the spark to jump thereacross. In this connection it will be observed that the current passes from the brush head 23 to each of the distributing contact brushes 32 simultaneously with the passage of current from those portions of the ring between the cams 21 to the roller contact 37.

It is believed that in view of the foregoing description, a further detailed description of the operation of the invention is entirely unnecessary. Likewise it is thought that the advantages of the invention will be readily apparent. However, at this point special attention is directed to the compact manner of forming the device which serves as a combination coil, distributor, interrupter and a condenser. By reason of the construction it will also be observed that there are no loose or moving wires which would have a tendency to affect the efficiency of the operation.

As many changes could be made in the above construction and many apparently widely different embodiments of this invention could be made without departing from the scope thereof, and it is intended that all matter contained in the above description or shown in the accompanying drawings shall be interpreted as illustrative and not in a limited sense. It is also to be understood that the language used in the following claim is intended to cover all the generic and specific features of the invention described and all statements of the scope of the invention, which, as a matter of language might be said to fall therebetween.

What is claimed is:

An apparatus of the kind set forth comprising a pair of casings, the one being rotatably mounted within the other, an induction coil carried within the rotatably mount-

ed casing, one terminal of the primary of said coil being grounded to the casing, a ring centrally disposed on top of said rotatable casing and formed on its upper face with a plurality of uniformly spaced cam elements, the remaining terminal of the primary of the said induction coil being connected to this ring, a cover removably secured to the outer casing and inclosing the inner casing therein, binding posts carried by said cover and disposed at equi-angular distances thereon, contact elements electrically connected with the binding posts and carried on the inner face of the cover, a sliding contact element carried by the inner casing for engagement with the first said contact elements when the casing is rotated, one terminal of the secondary of the induction coil being connected to this last said contact element and the remaining terminal being grounded to the inner casing, a screw threadingly engaged in the cover member and passing therethrough, a binding post carried by the cover member with which the screw is electrically connected, a rocker arm pivotally mounted on the cover member, a roller contact carried by the rocker arm and bearing upon the said ring and cam elements thereof when the inner casing is rotated, and a contact member carried by the rocker arm at the end remote from the roll, the last said contact member being brought into contact with and separated from the said screw when the inner casing is rotated, the screw providing adjustment to position it for contact with the last said contact member when the roll on the rocker arm rests on the ring between the cam element thereof.

In testimony whereof I affix my signature.
JAMES KELLY.
